UNITED STATES PATENT OFFICE

98,913

DESIGN FOR A COMBINATION DESK UNIT

Albert S. Brand, Boston, and David J. La France, Cambridge, Mass., assignors to The Carter's Ink Company, Cambridge, Mass., a corporation of Massachusetts

Application January 31, 1936, Serial No. 60,934

Term of patent 7 years

To all whom it may concern:

Be it known that we, Albert S. Brand and David J. La France, citizens of the United States and residents, respectively, of Boston, in the county of Suffolk and State of Massachusetts, and of Cambridge, in the county of Middlesex and State of Massachusetts, have invented a new, original, and ornamental Design for a Combination Desk Unit, of which the following is a specification, reference being had to the accompanying drawing, forming part thereof.

The figure is a view in perspective of a combination desk unit showing our new design.

We claim:

The ornamental design for a combination desk unit, substantially as shown.

ALBERT S. BRAND.
DAVID J. LA FRANCE.
